UNITED STATES PATENT OFFICE.

LOUIS P. SMITH AND JAMES H. HEAVERSIDE, OF CLEVELAND, OHIO.

PAVEMENT.

1,093,738.

Specification of Letters Patent.

Patented Apr. 21, 1914.

Application filed March 2, 1914. Serial No. 822,094.

To all whom it may concern:

Be it known that we, LOUIS P. SMITH and JAMES H. HEAVERSIDE, citizens of the United States of America, residing at Cleveland, in the county of Cuyahoga and State of Ohio, have invented a certain new and useful Improvement in Pavements; and we do hereby declare the following to be a full, clear, and exact description of the invention, such as will enable others skilled in the art to which it pertains to make and use the same.

This invention relates to new and useful improvements in the art of paving, and particularly to a new and improved means for providing a pavement above the ties and adjacent to the rails of a street railway.

The object of the invention is to provide means for supporting a pavement independently of the ties or rails so that the movement of the ties or rails will not disturb or displace the pavement supported by said means.

With this object in view, and with the intention of securing other advantages which will hereinafter appear, this invention consists in the features of construction and combination of parts hereinafter described in the specification, pointed out in the claims and illustrated in the accompanying drawings.

In the accompanying drawings, Figure 1 is a view in section of a pavement embodying our invention. Fig. 2 is a section on line 2—2, Fig. 1. Fig. 3 is a view similar to Fig. 1 showing a modification of our invention. Fig. 4 is a section on line 4—4, Fig. 3.

Again referring to the drawings, 1 represents the road bed and 2 represents the ties which are laid in the customary manner on the said road bed, and the said ties support rails 3 which are arranged thereon and secured thereto in the usual manner. Our improved means comprises a plurality of devices which are arranged over the ends of the ties at each side of each rail and each device comprises an inverted U-shaped member or chair having a top portion 7 and leg portions 8. The said leg portions 8 are longer than the depth of the tie so that the top member is supported a distance above the tie so that an open space is left between the top surface of the tie and the said top member of the device. In the sides of the legs 8 are preferably formed openings 9, and

extending upwardly from each opening is a tube or pipe 10, and the upper end or mouth of said tube is arranged flush with the surface of the pavement. A suitable cap 11 is provided for closing the upper end of said tube. The object of the opening in the legs 8 is to permit a tamping bar to be inserted into the space inclosed by the said chair or supporting device so that the earth around the ends of the ties may be tamped from time to time when necessary. The tubes which extend up from said openings provide passageways for guiding the tamping bar to the said openings so that the said openings are always accessible and the ties can be tamped without removing any of the paving blocks. Also the tubes provide means for supplying additional earth or ballast for the ends of the ties. After the devices have been put in position so as to form an arch over the ends of the ties at each side of each rail and particularly over the ends of the ties adjacent to the fish-plates which secure the ends of the rails together, the pavement 12 is laid on top of the said devices in the usual manner.

The advantages of our improved supporting devices will be readily understood. As is well known, when a car passes over the rails the ties immediately below the car are caused to bow down by the weight of the car and the outer ends of the ties are caused to lift up above their normal position and where the paving blocks rest directly upon the ends of the ties or upon the ballast which rests directly on the ties, the upward movement of the ends of the ties forces the paving blocks in the immediate vicinity of the said ends above the level of the rest of the paving. When the ends of the ties settle back to their normal position there is of course nothing to draw the paving blocks back to their original position so they remain above the level of the rest of the pavement and are a serious impediment, and oftentimes a menace to traffic on the street. Now by providing our improved devices for supporting the paving blocks adjacent to the ends of the ties the said paving blocks are supported above and out of contact with the said ties and the open space between the top of each device and the top of the tie affords ample space for the free up-and-down movement of the ends of the tie without permitting it to come in contact with the paving blocks.

In Figs. 3 and 4 is shown a modified form

of the invention. In this construction the legs of each supporting device are made sufficiently long to bring the top of the device almost flush with the surface of the surrounding pavement. A plate 14 is then laid on top of a number of the devices, taking the place of the paving blocks, and the upper surface of said plate will be flush with the surrounding pavement. As no pavement is placed on top of the plate 14 the upper surface of the plate is preferably corrugated or otherwise roughened so that horses can get a foothold thereon, and that it may also afford proper traction for self-propelled vehicles. Openings 16 are provided in the said plate communicating with the tubes 10 and caps 15 are provided for closing said openings.

What we claim is:—

- 20 1. The combination with a road bed, ties arranged thereon and rails arranged on said ties, of means for supporting the pavement adjacent to said ties, said means comprising a device consisting of a chair adapted to arch a tie and form an open space above the tie and below said chair to permit the upward and downward movement of the tie.
- 25 2. The combination with a road bed, ties arranged on said road bed and rails carried by said ties, of means for supporting the pavement adjacent to the rails and above the ends of the said ties, said means comprising a series of devices arranged at each side of the rail, each device comprising a horizontally arranged top member and a pair of downwardly extending legs, the said legs being adapted to straddle the end of a tie and support the top member of the device a distance above the tie leaving a free space between the tie and the top member of the device.
- 30 3. The combination with a road bed, ties arranged on said road bed and rails carried by said ties, of means for supporting the pavement adjacent to the rails and above the ends of the said ties, said means comprising a series of devices arranged at each side of each rail, each device comprising a horizontally arranged top member and a pair of downwardly extending legs, the said legs be-

ing adapted to straddle the end of a tie and support the top member of the device a distance above the tie leaving a free space between the tie and the top member of the device and tamping openings arranged in the sides of said legs.

55

4. The combination with a road bed, ties arranged on said road bed and rails carried by said ties, of means for supporting the pavement adjacent to the rails and above said ties, said means comprising a series of devices arranged at each side of each rail and adapted to arch the ends of the said ties, said devices being provided with openings in the sides thereof, tubes extending upwardly from said openings, and means for closing the upper end of said tubes.

60

5. The combination with a road bed, ties arranged on said road bed and rails carried by said ties, of means for forming a pavement adjacent to the rails and above the ends of the ties, said means comprising a plate arranged to extend longitudinally of each rail, legs extending downwardly from said plate and adapted to support said plate a distance above the ends of the ties leaving an open space between the plate and the ends of the ties and having the upper surface of the plate flush with the surrounding pavement, openings formed in said plate and covers for closing said openings.

70

6. A device for supporting pavement above ties of a railway track consisting of an inverted U-shaped chair comprising a horizontally arranged member and a pair of downwardly extending legs arranged to straddle a tie or a series of ties, the said legs being long enough to support the top member above and out of contact with the tie or ties.

75

In testimony whereof, we sign the foregoing specification, in the presence of two witnesses.
